ELECTRIC FENCE TESTER

Howard Langlie and Albert T. Berg, Jr., Ellendale, Minn.,
assignors to North Central Plastics, Inc., Ellendale,
Minn., a corporation of Minnesota

Filed Nov. 8, 1966, Ser. No. 4,580

Term of patent 14 years

(Cl. D52—1)

Fig. 1.

Fig. 4.

Fig. 5.

FIGURE 1 is a perspective view of an electric fence tester showing our new design;

FIGURE 2 is a top plan view of our tester;

FIGURE 3 is a bottom plan view of our tester;

FIGURE 4 is an end elevational view taken from the left;

FIGURE 5 is an end elevational view taken from the right, and

FIGURE 6 is a side elevational view.

In FIGS. 4, 5 and 6 the probe portion of the tester has been shown fragmentarily for convenience of illustration.

We claim:

The ornamental design for an electric fence tester, as shown and described.
